CARRYING AND DISPENSING DEVICE FOR
SPOOL MOUNTED WIRE

Gene W. Baker, 1817 76th St., Des Moines, Iowa

Filed Dec. 14, 1961, Ser. No. 159,277

6 Claims. (Cl. 242—86.5)

Electrical contractors experience great inconvenience on jobs which require numerous types and sizes of wire. The wire being placed in a structure is taken from individual boxes and spools and the electrician carries these sometimes heavy boxes of spools from place to place throughout the structure wherever the wire is being needed. The wire is not easily controlled as it is taken from these boxes or spools.

Therefore, the principal object of my invention is to provide a carrying and dispensing device for spool mounted wire which will permit a plurality of spools of wire to be carried from place to place without difficulty.

A further object of my invention is to provide a carrying and dispensing device for spool mounted wire that will permit selective and independent dispensing of wire from a plurality of spools without removing the spools from their mounted positions on a movable carrying structure.

A still further object of my invention is to provide a carrying and dispensing device for spool mounted wire which will accommodate a plurality of spools and which will permit the independent replacement of individual spools.

A still further object of my invention is to provide a carrying and dispensing device for spool mounted wire which will permit wire to be dispensed from one of a plurality of spools without actuating the remaining spools of wire.

A still further object of my invention is to provide a carrying and dispensing device for spool mounted wire which is readily mobile in the carrying operation and which is held against movement during the wire dispensing operation.

A still further object of my invention is to provide a carrying and dispensing device for spool mounted wires which will accommodate spools of different diameters and which will accommodate spools having different axial bores.

A still further object of my invention is to provide a carrying and dispensing device for spool mounted wire wherein the individual spools can be easily attached to or removed from the supporting structure.

A still further object of my invention is to provide a carrying and dispensing device for spool mounted wire that is economical of manufacture, durable in use, and refined in appearance.

These and other objects will be apparent to those skilled in the art.

My invention consists in the construction, arrangements, and combination, of the various parts of the device, whereby the objects contemplated are attained as hereinafter more fully set forth, specifically pointed out in my claims, and illustrated in the accompanying drawings, in which:

FIG. 1 is a perspective view of my device with a plurality of spools mounted thereon;

FIG. 2 is a partial sectional view of my device taken on line 2—2 of FIG. 1;

FIG. 3 is a partial sectional view of my device taken on line 3—3 of FIG. 1; and

FIG. 4 is a perspective view of my device in an upright position.

I have used the numerals 10 and 12 to designate two parallel L-shaped bars which are comprised of elongated straight portions 14 and handle portions 16 which are

2

disposed at right angles to the straight portions at one of the ends thereof. I will describe my device as oriented in the position of FIG. 1 but it is understood that this orientation of the various components of the unit is changed when the unit is placed in the upright position of FIG. 4. Rubber cups 18 are frictionally secured to the lower ends of the handle portions 16 of bars 10 and 12 and the function of these cups 18 will be described hereafter.

A vertically disposed plate 20 is secured near its lower edge to the ends of bars 10 and 12 opposite to handle portions 16. Plate 20 can be secured to bars 10 and 12 by welding or the like. A plurality of bars 22 extend between the parallel bars 10 and 12 in spaced relation to each other. The ends of bars 22 can be welded to the bars 10 and 12. Bars 22 can be uniformly spaced and are parallel to each other. An arcuate shaped depression 24 extends downwardly at the center of each of the bars 22. As shown in FIGS. 1, 2 and 3, a finger 25 is punched upwardly out of depression 24 on the longitudinal axes of the bars 22. As shown in FIG. 3, finger 25 divides the arcuate shaped depressions 24 into two supporting surfaces 26 and 28.

As shown in FIGS. 1 and 2, L-shaped brackets 30 are supported on top of each of the bars 22. Brackets 30 are comprised of a substantially straight portion 32 and a handle portion 34 which extends downwardly from the outer respective ends of the brackets. Two separate elongated slots 36 extend through the straight portions 32 of each bracket 30 along the longitudinal axis thereof. Conventional nuts 37 can be welded or otherwise secured to the bottoms of bars 22 below the slots 36 in brackets 30. A suitable bolt 38 extends downwardly through slots 36 and a suitable aperture in bars 22 to be threadably mounted in each one of the nuts 37. Springs 40 can be positioned between the top of the bracket 30 and the heads of each bolt 38 so that tension in a downward direction can be exerted by the springs on the brackets. The tension in spring 40 can be selectively adjusted by adjusting the position of bolts 38 in nuts 37. The tension in springs 40 will not prevent the sliding movement of the brackets 30 with respect to the individual bars 22, but the springs do serve to yieldably resist this sliding action.

Brackets 42 can be welded to the ends of bars 10 and 12 adjacent plate 20 and can extend downwardly from the bars in parallel relation. An axle 44 is rotatably secured in conventional fashion at the lower end of brackets 42 and wheels 46 are secured in conventional fashion to the outer ends of axle 44. Thus, the wheels 46 and the handle portions 16 of bars 10 and 12 serve to maintain the straight portions 14 of the bars in a substantially horizontal position when the unit is disposed as shown in FIG. 1. The forwardmost point of the wheels 46, as shown in FIG. 1, should not extend beyond the forward surface of plate 20. This will enable the plate 20 to support the entire unit on a horizontal surface when the bars 10 and 12 are moved to a vertical position as shown in FIG. 4.

The normal operation of my device is as follows: The electrician can move each of the brackets 30 to an "open" position as depicted in FIG. 2. This position of bracket 30 is achieved by sliding the bracket outwardly from the center depression 24 in bar 22. In FIG. 4, I have shown a plurality of spools 48, 50, 52, 54, 56 and 58 mounted on my device. In FIG. 1, spools 56 and 58 have been removed to more fully illustrate the structure of the unit. The spools may have center openings which vary in diameter. Accordingly, a stud shaft 60 is movably inserted into the center opening of spool 54 and a stud shaft 62 of a different diameter is inserted into the center opening of spool 52. As shown in FIG. 3, each of the shafts 60 and 62 are long enough to span the dis-

tance between a supporting surface 28 in one depression 24 and a supporting surface 26 in an adjacent depression 24. It should also be noted in FIG. 3 that the finger 25 prevents the adjacent ends of shafts 60 and 62 from engaging each other.

After the various spools of wire have been mounted in the respective depressions 24 on bars 22, the brackets 30 can be moved inwardly towards the center of the unit over the depression 24 to prevent the shafts upon which the spools are mounted from moving out of their supported positions within the various depressions 24. A bracket adjacent the exposed end of spool 54 in FIG. 1 is shown to be in this "closed" position. After the various spools have been secured to the unit in this manner, the electrician can then grasp the handle portions 16 of bars 10 and 12 to wheel the unit to any desired location. The unit can be tilted upon plate 20 as shown in FIG. 4, if the wire dispensing operation is not to begin immediately. When the electrician reaches his work station with the unit, the bars 10 and 12 are lowered to a horizontal position, as shown in FIG. 1, whereupon the unit is supported by the wheels 46 and the two handle portions 16. The electrician can then begin to reel wire from any one of the spools. The rubber cups 18 on the lower ends of handle portions 16 prevent the unit from moving laterally as the electrician pulls wire from the various spools. Since the fingers 25 in the depressions 24 of bars 22 completely separate the ends of these spool supporting shafts 60 and 62, each individual spool can be independently rotated without causing any rotation of adjacent spools. It should also be noted that wire can be dispensed from the spools from either side of the unit. If all of the wire is taken from one of the spools, the electrician can merely move the brackets 30 which are securing the empty spool from a "closed" to an "open" position. The spool is then removed and another spool can be put in its place without affecting or moving the remaining spool. Again, the depressions 24 in the bars 22 will accommodate spool supporting shafts of varying diameters so that a spool having a center opening diameter of one dimension can be substituted for a second spool having a center opening diameter of another dimension. When space requirements prevent my unit from assuming the horizontal position in FIG. 1, the unit can be moved to the vertical position of FIG. 4 during the dispensing operation. However, the horizontal position in FIG. 1 is the preferred dispensing position.

Thus, from the foregoing, it is seen that my device will accomplish at least all of its stated objectives.

Some changes may be made in the construction and arrangement of my carrying and dispensing device for spool mounted wire without departing from the real spirit and purpose of my invention, and it is my intention to cover by my claims, any modified forms of structure or use of mechanical equivalents which may be reasonably included within their scope.

I claim:

1. In a device of the class described, two parallel horizontal bars, one end of said bars terminating in a downwardly extending portion to support one end of said bars, wheel members on the other end of said bars to support the other end thereof, a plurality of cross members extending between said bars in parallel spaced relation, a downwardly extending arcuate depression in each of said cross members, said arcuate depressions adapted to receive the ends of shafts having varying diameters,

4
a finger element protruding from the center of each of said arcuate depressions, and a bracket element movably secured to said cross members and adapted to extend across said arcuate depressions at times.

5
2. The structure of claim 1 wherein rubber cups are on the lower ends of the downwardly extending portions of said bars to resist lateral movement of said bars.

10
3. The structure of claim 1 wherein a vertical plate is secured to the ends of said bars adjacent said wheels whereby said bars can be supported in a vertical position at times when said plate is moved to a horizontal position.

15
4. In a device of the class described, two parallel horizontal bars, one end of said bars terminating in a downwardly ex-
tending portion to support one end of said bars, wheel members on the other end of said bars to support the other end thereof,

20
a plurality of cross members extending between said bars in parallel spaced relation, a downwardly extending arcuate depression in each of said cross members, said arcuate depressions adapted to receive the ends of shafts having varying diameters, and a bracket element movably secured to said cross members and adapted to extend across said arcuate depressions at times.

25
5. In a device of the class described, two parallel horizontal bars, one end of said bars terminating in a downwardly ex-
tending portion to support one end of said bars, wheel members on the other end of said bars to support the other end thereof,

30
a plurality of cross members extending between said bars in parallel spaced relation, a downwardly extending arcuate depression in each of said cross members, said arcuate depressions adapted to receive the ends of shafts having varying diameters, means secured to said cross members and extending into said arcuate depressions to separate the adjacent ends of two shafts supported within said de-
pressions,

35
and a bracket element movably secured to said cross members and adapted to extend across said arcuate depressions at times.

40
6. In a device of the class described, two parallel horizontal bars, one end of said bars terminating in a downwardly ex-
tending portion to support one end of said bars, wheel members on the other end of said bars to support the other end thereof,

45
a plurality of cross members extending between said bars in parallel spaced relation, and means on said cross members for receiving and supporting the ends of a plurality of shafts having their longitudinal axes perpendicularly disposed to the axis of rotation of said wheel members.
